CLAIM

The ornamental design for a pet chew toy, as shown and described.

DESCRIPTION

FIG. 1 is a top perspective view of a pet chew toy in accordance with the present design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a back elevation view thereof.

The broken lines in the drawings illustrate portions of the pet chew toy that form no part of the claimed design.
